UNITED STATES PATENT OFFICE.

EDWARD A. TUTTLE, OF NEW YORK, N. Y.

DESIGN FOR A HOT-AIR AND VENTILATING REGISTER.

Specification forming part of Design No. 5,470, dated January 9, 1872.

To all whom it may concern:

Be it known that I, EDWARD A. TUTTLE, of the city of New York, in the county and State of New York, have invented a new and original Design for Hot-Air and Ventilating Registers, of which the following is a specification:

The nature of my invention is fully represented in the accompanying photographic illustration, to which reference is made.

The border of the register and the central figure are concentric circles *a c*. Between these the design is composed of interlaced scroll-work or arabesques. Immediately connected with the inner circle, on four sides thereof, is a figure, *d*, like a clover-leaf in form, or having four projecting portions formed by

a corresponding number of alternating depressions. Interlocked with each two of these is a lyre-shaped figure, *e*, whose volute wings as well as central part join the outer circle. Interlaced with the lyres, and equidistant between the concentric circles, is a connected series of double volutes or scrolls, *o*.

All these figures save the circles are flourished to fill up the design.

What I claim as my design is—

The arrangement of the circles *a c* and figures *d e o*, as shown and described.

EDWARD A. TUTTLE.
